Primary Examiner — Philip S Hyder(74) *Attorney, Agent, or Firm* — Breiner & Breiner,
L.L.C.(57) **CLAIM**

The ornamental design for a wire shear anvil tool, as shown and described.

DESCRIPTION

FIG. 1 is a front perspective view of a wire shear anvil tool, showing the new design in a closed position;

FIG. 2 is a front perspective view thereof, showing the tool in an open position;

FIG. 3 is a left side elevation view thereof;

FIG. 4 is a rear elevation view thereof;

FIG. 5 is a right side elevation view thereof;

FIG. 6 is a bottom perspective view thereof; and,

FIG. 7 is a top plan view thereof.

The broken lines depict aspects of the wire shear anvil tool in which the design is embodied that are not considered part of the claimed design.

1 Claim, 4 Drawing Sheets(56)
